Primary Examiner — Lilyana Bekic*Assistant Examiner* — Lee D. Starr(74) *Attorney, Agent, or Firm* — Dorsey & Whitney LLP(57) **CLAIM**

We claim the ornamental design for an oral irrigator base, as shown and described.

DESCRIPTION

FIG. 1 is a front isometric view of an oral irrigator base.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines illustrate portions of the oral irrigator base that form no part of the claimed design.
